UNITED STATES PATENT OFFICE.

JOHN C. MOON, OF ST. LOUIS, MISSOURI.

THREAD-CUTTER.

1,232,708.

Specification of Letters Patent. Patented July 10, 1917.

Application filed May 18, 1916. Serial No. 98,323.

To all whom it may concern:

Be it known that I, JOHN C. MOON, a citizen of the United States, residing at the city of St. Louis, State of Missouri, have invented a certain new and useful Improvement 5 in Thread-Cutters, of which the following is a full, clear, and exact description, such as will enable others skilled in the art to which it appertains to make and use the same, reference being had to the accompanying drawings, forming part of this specification, in which—

Figure 1 is a side elevational view of my improved pipe threading machine.

Fig. 2 is a top plan view of a portion 15 thereof.

Fig. 3 is a vertical sectional view through the device for clamping the rod or pipe to be threaded.

Fig. 4 is a side elevational view partly in section of said clamping device.

This invention relates to a new and useful improvement in thread cutters for cutting threads upon the ends of rods or pipes, the 25 object being to construct a machine of the character described which will simultaneously cut threads on both ends of the rod or pipe. With these objects in view, my invention consists in the construction and arrangement and combination of the several 30 parts, all of which will be described and afterward pointed out in the claims.

In the drawings, 1 indicates a bench or table on which are mounted two castings 2 35 forming bearings for shafts 3 which derive motion through the medium of pulleys 4 and belts 5, said shafts being driven in opposite directions. The inner end of each shaft is made hollow and provided with a flange 3^a (see Fig. 4) the face of which flange is 40 provided with guides to receive radially movable cutters or chasers 6. These cutters are held in position by suitable bolts 7 and are slotted lengthwise so as to permit inward and outward movement. Springs 8 are arranged in the slots with their inner 45 ends resting against bearing blocks which are seated upon the bolts 7, the energies of said springs being directed at all times to move the cutters outwardly. The periphery of flange 3^a is also provided with grooves forming guide ways for longitudinally movable blocks 9, the latter being provided with inclined or beveled outer ends which are 50 designed to engage the inclined outer ends of the cutters 6, and force the same inwardly

into cutting position. Blocks 9 are confined by the flange of a sliding collar 10 mounted on the inner end of shaft 3, said sliding collar being keyed to the shaft so as to rotate therewith and having an annular groove in which fit the prongs of a bracket 11 (see Fig. 2), which bracket is slidably mounted upon a rod 12. The rod 12 is secured in suitable lugs 2^a on the castings 2 and carries collars 13 adjustably mounted thereon. The purpose of the construction above described is as follows:

When the shaft 3 is being retracted or moved outwardly, the parts are in the full 70 line position shown in Fig. 4 in which the cutters 6 occupy their outer position. The continued outward movement of the shaft will cause the yoke or bracket 11 to contact with the outermost collar 13, whereupon the 75 collar 10 will have a relative inward movement on shaft 3, causing the inclined outer ends of blocks 9 thereof to engage the inclined outer ends of the cutters 6 and force said cutters inwardly into cutting position. 80 The flange 3^a forms a stop for this closing movement of the collar 10. When the cutters are closed, they are in position to engage a pipe or rod to cut threads thereon when the shaft 3 is moved inwardly.

Assuming now that a pipe or rod is in position and the shaft 3 is moved inwardly, the thread will be cut thereon until the yoke or bracket 11 strikes the innermost collar 13 when the collar 10 will be moved relatively back on shaft 3, permitting the cutters to open and thus enabling the quick retractive movement of the shaft 3 and its carried parts.

The above description applies to the construction at each end of the machine, there being two cutters, one for operating on opposite ends of the same rod or pipe, and, as before stated, these cutters are intended 90 to be rotated in opposite directions in order 100 to properly cut the threads.

The means for feeding the cutters inwardly and then retracting them consists of operating handles 15 (see Fig. 1) connected to a pinion 16 mounted in fixed bearings, which pinion co-operates with racks 17 on the ends of the oppositely extending rods 18. The outer ends of these rods are connected to levers 19 pivoted in suitable brackets 20 secured to bed plates 1, the upper ends of 110 levers 19 being pivotally connected to collars 21 loosely mounted upon the shanks of

yokes 22 which latter are pivoted to the ends of shafts 3. Jam nuts 23 hold these collars 21 in position. When the handles 15 are moved in a clockwise direction, the shafts 3 will be moved inwardly. When this cutting action is completed, the cutting jaws 6 will be moved outwardly and the handles 15 can be quickly moved in a counter-clockwise direction so as to move the shafts 3 outwardly in readiness for another operation. The operator can of course "feel" the cutting action on the inward movement of the shaft and assist such action by pressure on handles 15 which pressure is necessary in starting the cutting.

The means for holding the pipe or rod in position to be operated upon is best shown in Figs. 3 and 4, wherein it will be observed that a bearing block 25 is supported by a downward extension of the frame work which supports the table 1. This bearing block, or rather these two bearing blocks, as the mechanism for clamping the rods or pipes in position, about to be described, is duplicated for each end of the rods or pipes, provides a pivotal support for arms 26 extending through openings in the bed plate 1. 27 indicates a cam keyed to the shaft 28, on one end of which shaft is arranged an operating handle 29. 30 indicate clamping blocks pivoted at 31 between the arms 26 and having rollers 32 at their lower ends which coöperate with the cam 27. These clamping jaws are bifurcated at their lower ends between the prongs of which bifurcations said rollers 32 are mounted and in which bifurcations the cam 27 operates, as shown in Fig. 3. Clamping jaws 30 are connected together at their lower ends by means of springs 33 so that the rollers 32 are at all times in yielding engagement with the cam 27. The upper ends of the clamping jaws 30 are provided with semi-circular recesses 30^a which are designed to register with correspondingly shaped recesses 26^a formed in the opposite side edges of a cross bar 26^b, which connects the upper ends of the arms 26. The pipe to be threaded is indicated at A. in Fig. 3, and the pipe being threaded, or in position to be threaded, is indicated at B. in said figure. When the parts are in the position shown in Fig. 3, it will be observed that the clamping jaw at the left is open to receive the pipe A. (or if said pipe had previously been threaded, to permit its removal, and the introduction of an unthreaded pipe in position), and that the clamping jaw at the right is in clamping position holding the pipe B. against rotation, while it is being threaded. The cam 27 forces the clamping jaws into clamping position and springs 33 open either companion jaw when its companion is in clamping position.

Thus it will be seen that the clamping ac-

tion of the jaws is positive, it being possible to exert considerable power on the clamping jaws through the cam, while the opening movement of the jaws depends upon the spring action.

In order to determine the alinement of a pipe or rod with the cutters 6, there is a stop 26^c on each side of one of the arms 26 which stop coöperates with the brackets 34 mounted on the bed plate 1. These brackets 34 may be adjustably mounted upon the bed plate 1 by slot and pin connections to enable their inward and outward adjustment, or removable plates 35 may be arranged to coöperate with the faces of stops 26^c. This alinement of the pipe or rod to be threaded with the cutters 6 is quite important and the stops for arresting the arms 26 in their extreme position must be accurately placed. The handle 29 serves as a means for rocking the arms 26 to and fro and for this purpose it is only necessary for the operator to pull the handle toward him or push it away from him until the arms are arrested by their respective stops; then, by depressing or lifting the arm, as the case may be, the pipe which has been threaded is released, and the pipe to be threaded is clamped in position. The released pipe may be removed and another pipe to be threaded placed in position in the jaws of the opened clamps. It is immaterial whether the arms 26 are first rocked and the handle 29 then depressed or raised, or the handle first depressed or raised and the arms 26 then rocked,—this is optional with the operator and the sequence of operations is consequently left to his discretion.

The clamping jaws are duplicated for each end of the pipe, and in order that they may be moved in unison, the shaft 28 is extended from one side of arms 26 to the other and, furthermore, said arms are connected together by a bracket 36 (see Fig. 4) so that they will move in unison.

In order to position the pipes or rods to be threaded, I provide two stops 40 (see Fig. 2) against which one end of the rod or pipe is placed when the clamping jaws are open.

I claim:

1. In a machine of the class described, the combination of a pair of oppositely disposed alined longitudinally movable shafts, radially movable cutters carried by each shaft, the outer ends of which cutters are inclined, means carried by and movable lengthwise upon each shaft for engaging the inclined outer ends of said cutters and forcing the same inwardly, yielding means for moving said cutters outwardly, manually operable means for simultaneously moving the shafts toward or away from each other and stops for limiting the lengthwise movement in both directions of the cutter actuating means carried by each shaft whereby the continued movement of the shaft effects an

inward or outward movement of said cutters dependent upon the direction of movement of said shaft.

2. In a machine of the class described, the combination of a pair of oppositely disposed alined longitudinally movable shafts, radially movable cutters thereupon, the outer ends of which cutters are inclined, a member carried by and movable longitudinally upon each shaft, parts of which member are inclined and bear directly against the inclined outer ends of the cutters, manually operable means for simultaneously moving both shafts toward or away from each other and stops for limiting the movement of the cutter actuating members upon the shafts in one direction so that the continued movement of the shafts will effect an inward movement of the cutters, and yielding means for moving the cutters outwardly.

3. In a machine of the character described, the combination of a rocking arm, a pair of clamping jaws pivotally mounted thereon and coöperating therewith, and means for rocking said arm, said means also controlling the opening and closing movement of said clamping jaws.

4. In a machine of the character described, the combination of a rocking arm, stops for limiting its rocking movement in each direction, a pair of clamping jaws pivotally mounted on said arm and coöperating therewith to grip a pipe or rod to be operated upon, a cam for controlling the opening and closing movement of said jaws, and means for holding said jaws in operative relation to said cam.

5. In a machine of the character described, the combination of a rocking arm, stops for limiting its rocking movement in each direction, a pair of clamping jaws piv-

otally mounted on said arm and coöperating therewith to grip a pipe or rod to be operated upon, a cam for controlling the opening and closing movement of said jaws, a 45 handle for rocking said arm and moving said cam and springs connected to said jaws whereby they are held in yielding operative relation to said cam.

6. In a machine of the class described, the combination with two positively revolving shafts, of means for moving said shafts toward and away from each other, cutters carried by said shafts, means for rendering said cutters effective or ineffective, and pipe gripping means arranged between the inner ends of said shafts, which gripping means comprises a rocking arm, a pair of clamping jaws pivotally mounted thereon and coöperating therewith, and means for rocking said arm, which means control the opening and closing movement of said clamping jaws.

7. In a machine of the class described, the combination with a pair of oppositely disposed thread cutters, of pipe gripping means positioned between said cutters, which gripping means includes a rocking member, a pair of clamping jaws pivotally mounted on said member and coöperating therewith to grip a pipe or rod to be threaded, and means for rocking said member, which means control the opening and closing movement of the clamping jaws.

In testimony whereof I hereunto affix my 75 signature in the presence of two witnesses, this 15th day of May, 1916.

JOHN C. MOON.
